UNITED STATES PATENT OFFICE.

ETHEL MCGRATH, OF PELHAM HEIGHTS, NEW YORK.

DESIGN FOR A JAR OR SIMILAR CONTAINER.

Application filed December 8, 1925. Serial No. 15,688. Term of patent 3½ years.

To all whom it may concern:

Be it known that I, ETHEL MCGRATH, a subject of the King of England, residing at Pelham Heights, in the county of Westchester and State of New York, and doing business at 128 Corona Avenue, Pelham Heights, N. Y., have invented a new, original, and ornamental Design for a Jar or Similar Container, of which the following is a specification, reference being had to the accompanying drawings, forming part thereof.

I claim:

The ornamental design for a jar or similar container as shown.
